US00D621645S

(12) **United States Design Patent**
Johnson et al.

(10) **Patent No.:** **US D621,645 S**
(45) **Date of Patent:** **** Aug. 17, 2010**

(54) **GRAVITY FEED DISPENSER DISPLAY**

(75) Inventors: **Terry J. Johnson**, Chicago, IL (US);
John Schoemer, Elk Grove Village, IL (US); **Travis O. Johnson**, Chicago, IL (US)

(73) Assignee: **Gamon Plus, Inc.**, Elk Grove, IL (US)

(**) Term: **14 Years**

(21) Appl. No.: **29/355,536**

(22) Filed: **Feb. 9, 2010**

(57) **CLAIM**

The ornamental design for a gravity feed dispenser display, as shown and described.

DESCRIPTION

The sole FIGURE is a perspective view of a gravity feed dispenser display showing our new design.

The broken line showing is for the purpose of illustrating portions of the gravity feed dispenser display and forms no part of the claimed design.
